UNITED STATES PATENT OFFICE.

MAURICE S. ROSENFIELD, OF NEW YORK, N. Y.

METHOD OF CLEANING FILMS.

1,273,928.

Specification of Letters Patent. Patented July 30, 1918.

Application filed September 6, 1916. Serial No. 118,770.

To all whom it may concern:

Be it known that I, MAURICE S. ROSENFIELD, a citizen of the United States, residing in the borough of the Bronx, county of Bronx, city and State of New York, have invented a new and useful Improvement in Methods of Cleaning Films, of which the following is a specification.

The object of my invention is to provide means whereby a film will be thoroughly cleaned and dried before it is reeled.

This and further objects will more fully appear in the following specification and accompanying drawings considered together or separately.

I have illustrated my invention in the accompanying drawings, in which like parts are designated by similar reference characters in all of the figures, and in which,—

20 Figure 1 is a diagrammatic side elevation of my invention;

Fig. 2 is an enlarged sectional elevation of the moistener, shown at *e* in Fig. 1, the section being taken on the line 2—2 of Fig. 3;

25 Fig. 3 is a section on the line 3—3 of Fig. 2;

Fig. 4 is a top plan view of the moistener;

Fig. 4^a is a bottom plan view in detail of a modification;

30 Fig. 4^b is an elevation of the same;

Fig. 5 is a top plan view of the buffer;

Fig. 6 is a section of the same taken on the line 6—6 of Fig. 5;

Fig. 7 is a rear elevation of the same;

35 Fig. 8 is a top plan view of the feeder;

Fig. 9 is a longitudinal section of the same, taken on the line 9—9 of Fig. 8; and

Fig. 10 is an end elevation of the same.

In the drawing, *a* indicates a support on which is mounted a reel *b* carrying the film *c* to be cleaned. From the reel *b* the film is led to a coating device *d* and thence to the moistener *e*. From the moistener the film is carried to a buffer *f* where the coating and moisture are removed. Adjoining the buffer is a feeder *g* through which the film is led. The feeder draws the film through above mentioned devices, and drives a take-up reel *h* to which the end of the film is secured.

The reel *b* is the usual spool on which the film is wound after passing through the projecting machine.

The coating device *d* comprises a frame 1, in which is mounted a pair of rolls 2. The faces of the rolls are of less length than

the distance between the lines of sprocket openings in the film. These rolls are preferably composed of cork or some other suitable material, and before the film is passed through them, each is given a thin coat of wax or other similar material. The wax coating may be applied by rotating the rollers in contact with a lump of wax, or they may be painted with melted wax which is allowed to harden.

The rolls 2 are rotated by the passage of the film between them, and as it passes particles of wax from the rolls will be deposited upon both sides of it. The wax will adhere to the foreign matter on the film.

From the coating device *d* the film is drawn through the moistener *e*. The moistener comprises a base 3 upon which is mounted a standard 4. Carried on the standard is a tank 5 for containing a liquid, preferably tetrachlorid of carbon, with which the film is to be moistened. The tank is secured in place by a set screw 6. To the bottom of the tank is secured a pad holder 7 in which is a pad 8 of felt or other fibrous material. The pad projects below the bottom of the holder and is preferably of circular cross section, and of a diameter less than the distance between the lines of perforations 9 of the film *c*. Within the tank and communicating with the pad holder is a stand pipe 10 which is open at the top and extends above the surface of the liquid. A piece of wicking or other porous material 11 rests on the top of the stand pipe with one end depending downward in the pipe, and the other end immersed in the liquid. The liquid will be raised by the capillary attraction of the wick, and will be deposited drop-by-drop in the stand pipe and on the pad 8.

Slidably carried on the standard 4, is a pad carrier 12, within which is supported a pad 13 of material similar to that of the pad 8. The pad carrier is provided with a stand pipe 14 which is in communication with the bottom of the pad 13, and extends upward into and above the surface of the liquid in the tank 5. The stand pipe 14 carries a strip of wicking 15 similar to that carried by the standpipe 10, by means of which liquid is, by capillary attraction, deposited in the pad carrier, and by capillary attraction carried to the top of the pad 13 which is similar in diameter to the pad 8. A spring 16 normally holds the pad 13 in

engagement with the pad 8. A manually operated lever 17 is provided for lowering the pad carrier 12 against the tension of the spring so as to separate the pads 8 and 13 when it is desired to insert the film between them. Suitable guide rollers are carried on the frame and support the film during its passage through the moistener.

If desired, a hood 7^a, Figs. 4^a and 4^b, of 10 plush or other suitable material may be placed over the ends of the pads 8 and 13 and be secured in place by spring clips 8^a.

From the moistener the film is led to the buffer *f*. The latter is spaced a considerable 15 distance from the former so as to allow the film to dry during its travel from one to the other.

The buffer comprises a frame 18 similar 20 in every respect to the frame of the coating device, and consists of two side members 19, 19, and a base 20 which is secured to the support *a*. Mounted in the sides is a shaft 21 which carries a buff wheel 22 built up of disks of suitable material, clamped together. A shaft 21^a carries a rag wheel 23 which is composed of strips of chamois or other suitable material, which is clamped to the shaft with the ends forming the periphery of the wheel loose and unattached. The loose ends of the strips of the 25 wheel 23 engage the emulsified side of the film, and will reach into the minute cavities of such surface.

Mounted on one of the side frames 19, 30 and over the rag wheel is a chamber 24, open at top and bottom. A block of suitable absorbent, polishing material, such as chalk or magnesia, is carried in the chamber 24, and rests upon the face of the rag 35 wheel, so that as the latter is rotated the strips of which it is composed, will wipe off and carry particles of the polishing material with them. The wheels 22 and 23 are 40 geared together, and the shaft 22 carries a pulley by means of which the buff wheels are driven. A pair of guide rollers 25, 25 are mounted in the frame and direct the film to the feeding device *g*.

The feeder comprises a standard 26 carried on the support *a*, and on which is 45 mounted a box 27. Within the box is mounted a roller 28 carried on a shaft 29 which carries a pulley 30. Projecting from the front side of the box is a lip 31 which 50 carries a wiping surface 32. The wiping surface comprises a strip of felt or other suitable material secured to the lip in any desired manner.

Hinged to the top of the box 27 is a cover 60 33 which carries two rollers 34, 34, which, when the cover is in place, lie one on each side of the roller 28, and hold the film in engagement with said roller. The shaft 29 of the roller 28 is geared to the shaft of one or both of the rollers 34. The cover

carries at its front end a lip 35 covered by a wiper 36, similar to those on the box. To thread the film through the box 27, the cover is raised, the film is laid on the wiper 32, on the roller 28, and out through an 70 opening 37 in the rear end of the box. The cover is now closed, bringing the rollers 34, 34 down on the film and holding it in close contact with the drive roller. The wiper 36 engages the top of the film, and as it 75 is drawn into the box both the top and bottom surfaces will be cleared of any foreign substances. There is a latch 38 for holding the cover in place on the box.

The shaft 29 carries a pulley 39 which is 80 geared to a pulley 40 on the shaft 21^a of the buffer, and the buffer wheels 22 and 23 are geared together in any suitable manner.

From the feeder the film is wound upon the takeup reel *h* in the usual manner. 85

The operation of my improved method and apparatus is as follows:

The film passes through the device with its emulsified side uppermost.

The surfaces of the rolls 2, 2 are coated 90 with wax and as the film passes between them the wax will be caused to scale off and the minute scales will adhere to both sides of the film, and as the rolls are not as wide as the distance between the rows 95 of perforations 9 in the film, the wax scales will not be deposited in proximity to such holes.

When the waxed film reaches the moistener, the tetrachlorid or carbon with which 100 the pads are moistened, will dissolve the wax and spread it in a thin, even coating on both sides of the film. This coating will adhere to the foreign matter on the film, and as the moisture evaporates, the wax coating 105 will become friable and crumbly. When the coated film reaches the buffer wheels 22, 23, the coating will be nearly dry and the wheels which are traveling at a high rate of speed, will remove the wax and foreign 110 substances to which it adheres from the film. The lower surface of the film being non-porous and waterproof, will be effectively cleaned and dried by the ordinary buff wheel 22. The emulsified surface of 115 the film being pitted cannot be cleaned and dried by an ordinary wheel, but the loose ends of the chamois strips of the wheel 23 will search out the cavities in the surface and dust them with the absorbent material carried on the strips. The flicking action of the strips will brush the chalk from the cavities and from the film. Any chalk which may remain on the film will be wiped off by the wipers 32 and 36.

The rotation of the feed rollers 29 and 34 will draw the film through the various devices, and will drive the reel *h* to take up the film.

In accordance with the provisions of the 120

5 patent statutes, I have described the principle of my invention together with the apparatus, which I now consider to represent the best embodiment thereof, but I desire to have it understood that the apparatus shown is merely illustrative, and that the invention can be carried out in other ways without departing from the spirit of my invention.

10 Having now described my invention, what I claim as new and desire to secure by Letters Patent of the United States, is as follows:

11 1. A method of cleaning photographic 15 films, which consists in applying wax to the surface of the film, dissolving the wax, and then removing the wax.

12 2. A method of cleaning photographic 20 films, which consists in applying wax to the surface of the film, moistening the waxed surface, and then removing the wax and moisture.

13 3. A method of cleaning photographic 25 films, which consists in applying wax to the surface of the film, dissolving the wax, and then removing the wax, in the presence of an absorbent substance.

14 4. A method of cleaning photographic 30 films, which consists in applying wax to the surface of the film, dissolving the wax, and then removing the wax, in the presence of a finely divided absorbent material.

15 5. A method of cleaning photographic 35 films, which consists in applying wax to the surface of the film, dissolving the wax, and then removing the wax, in the presence of chalk.

16 6. A method of cleaning photographic 40 films, which consists in applying wax to the surface of the film, moistening the waxed surface, and then removing the wax and moisture, in the presence of an absorbent substance.

17 7. A method of cleaning photographic 45 films, which consists in applying wax to the surface of the film, moistening the waxed

surface, and then removing the wax and moisture, in the presence of chalk.

18 8. A method of cleaning photographic 50 films, which consists in applying wax to the surface of the film, moistening the waxed surface, and then removing the wax and moisture, in the presence of finely divided chalk.

19 9. A method of cleaning photographic 55 films, which consists in applying wax to the surface of the film, dissolving the wax, removing the wax and polishing the surface of the film, and then removing the polishing material.

20 10. A method of cleaning photographic 60 films, which consists in applying wax to the surface of the film, dissolving the wax, removing the wax, and polishing the surface of the film with an absorbent material.

21 11. A method of cleaning photographic 65 films, which consists in applying wax to the surface of the film, dissolving the wax, removing the wax, and polishing the surface of the film with a finely divided material.

22 12. A method of cleaning photographic 70 films, which consists in applying wax to the surface of the film, dissolving the wax, removing the wax, and polishing the surface of the film with a finely divided absorbent material.

23 13. A method of cleaning photographic 75 films, which consists in applying wax to the surface of the film, dissolving the wax, removing the wax, and polishing the surface of the film with chalk.

24 14. A method of cleaning photographic 80 films, which consists in applying a plastic material to the surface of the film, dissolving the same, and then removing said plastic material.

This specification signed and witnessed this 29 day of August, 1916.
